US00D860456S

(12) **United States Design Patent** (10) Patent No.: **US D860,456 S**
Buchanan et al. (45) Date of Patent: **** Sep. 17, 2019**

(54) **PLANTAR LAPIDUS PLATE**

- (71) Applicant: **Aristotech Industries GmbH**,
Luckenwalde (DE)
- (72) Inventors: **Matthew Buchanan**, Falls Church, VA
(US); **Albert E. Austin**, Millersville,
MD (US); **Emmanuel Anapliotis**,
Berlin (DE)
- (73) Assignee: **Aristotech Industries GmbH**,
Luckenwalde (DE)
- (**) Term: **15 Years**
- (21) Appl. No.: **29/580,690**
- (22) Filed: **Oct. 12, 2016**

CLAIM

The ornamental design for a plantar lapidus plate, as shown.

DESCRIPTION

FIG. 1 is a top perspective view of a plantar lapidus plate;
FIG. 2 is a top view thereof;
FIG. 3 is a bottom view thereof;
FIG. 4 is a front view thereof;
FIG. 5 is a rear view thereof; and,
FIG. 6 is a right side view thereof.

1 Claim, 3 Drawing Sheets

See application file for complete search history.
